UNITED STATES PATENT OFFICE.

MORRIS HIRSHFIELD, OF BROOKLYN, NEW YORK.

DESIGN FOR A SLIPPER.

60,670.

Specification for Design. Patented Mar. 21, 1922.

Application filed November 16, 1921. Serial No. 515,708. Term of patent 3½ years.

To all whom it may concern:

Be it known that I, MORRIS HIRSHFIELD, a citizen of the United States, and resident of the borough of Brooklyn, county of Kings, city and State of New York, have invented a new, original, and ornamental design for Slippers, of which the following is a specification.

In the accompanying drawings, Fig. 1 is a plan view of a slipper showing my new design, and Fig. 2 is a side elevation thereof.

It is to be understood that my claim includes all substantial equivalents of my design, as shown and described.

I claim:

The ornamental design for a slipper as shown and described.

MORRIS HIRSHFIELD.
